Primary Examiner — Brian N. Vinson(74) *Attorney, Agent, or Firm* — Notaro, Michalos & Zaccaria P.C.(57) **CLAIM**

The ornamental design for a square solar LED light, as shown and described.

DESCRIPTION

FIG. 1 is a top left perspective view of a square solar LED light showing my design therefor;

FIG. 2 is a top plan view thereof;

FIG. 3 is a bottom plan view thereof;

FIG. 4 is a left side elevational view thereof;

FIG. 5 is a right side elevational view thereof;

FIG. 6 is a front elevational view thereof; and,

FIG. 7 is a rear elevational view thereof.

The broken line portions of the disclosure represent unclaimed subject matter.
